UNITED STATES PATENT OFFICE

HENRY JOHNSON, OF BEATRICE, NEBRASKA

GRAVE MARKER

Application filed January 11, 1933. Serial No. 651,215.

This invention relates to a device designed for use in marking graves, the primary object of the invention being to provide a device of this character which may be readily and easily driven into the ground surface, and one which may be easily viewed, without the necessity of the person stooping to observe the reading matter on the card supported by the device.

10 An important object of the invention is to provide a device of this character which may be constructed of any suitable plastic material, the body portion thereof being formed with a recess for the reception of a card on which certain data is provided, so that the grave may be readily identified.

15 A further object of the invention is to provide means for securing the card within the recess, in such a way that the card will be protected against the elements and at the same time provide a securing device that will not rust or tarnish.

20 With the foregoing and other objects in view, which will appear as the description 25 proceeds, the invention resides in the combination and arrangement of parts and in the details of construction hereinafter described and claimed, it being understood that changes in the precise embodiment of the invention 30 herein disclosed, may be made within the scope of what is claimed, without departing from the spirit of the invention.

Referring to the drawing:

25 Figure 1 is a front elevational view of a 30 grave marker constructed in accordance with the invention.

Figure 2 is a side elevational view thereof.

Figure 3 is a sectional view taken substantially on line 3—3 of Figure 1.

35 Referring to the drawing in detail, the reference character 5 designates the body portion of the marker, which is formed with a wide head section 6 and a tapered section 7, the tapered section 7 being so constructed 40 that it may be readily driven into the ground surface.

45 As clearly shown by Figure 2 of the drawing, the head section has its front surface beveled as at 8, so that the printed matter 50 contained on the card supported by the de-

vice, may be readily viewed from a standing position, eliminating the necessity of the person stooping to read the card.

This head is formed with a rectangular cut out portion 9 which is of a size slightly greater than the card supported therein, thereby providing a space, for the reception of the rubber backing strip 10.

This rubber backing strip is so constructed that when it is positioned within the cut out portion 9, the ends and edges thereof will bend outwardly, as clearly shown by Figure 3, thereby providing what might be termed a frame for the card.

The card is indicated by the reference character 11, and is covered by the translucent member 12, which in the present showing is in the form of glass. This member 12 is of a size to completely cover the card 11, and set up a binding action between the rubber backing strip 10 and walls of the cut out portion 9.

55 After the card has been properly positioned, and the translucent member 12 placed thereover, a layer of cement indicated at 13, is placed over the meeting edges of the rubber backing strip 10, and member 12, thereby securely sealing the card against the elements.

60 The card is provided with certain indicia to indicate the name of the person buried, date of death, and age at the time of death.

65 It will be seen that due to this construction, a durable and weather proof marker is provided, which will not tarnish, and one which will preserve the card supported therein.

Having thus described the invention what is claimed is:

70 1. A marker of the class described, comprising a body portion, a head forming a part of the body portion, said head having a cut out portion formed in the face thereof, a 75 backing strip positioned within the cut out portion, the edges of the backing strip covering the wall of the cut out portion, a card carrying indicia, positioned on the backing strip, a translucent cover positioned over the card, and the adjacent edges of the backing 80

strip and translucent member being cemented together.

2. A marker of the class described, comprising a body portion including a wide head and a tapered portion, the head having a cut out portion, a rubber backing strip positioned in the cut out portion, the edges of the strip extending outwardly lining the walls of the cut out portion, a card having indicia thereon, positioned against the backing strip and between the outwardly extended edges of the backing strip, a translucent cover on the card, and the adjacent edges of the translucent cover and backing strip being cemented together.

3. A marker of the class described comprising a body portion, a head formed at one end of the body portion, the face of the head being beveled and formed with a cut out portion, a backing strip fitted in the cut out portion, portions of the backing strip covering the wall of the cut out portion, a card carrying indicia fitted on the backing strip, a translucent cover member positioned over the card and the edges of the translucent cover and backing strip, being cemented together.

4. A marker of the class described comprising a body portion, a wide head formed with a cut out portion, a rubber backing strip larger than the cut out portion, portions of the backing strip extending outwardly when the backing strip is positioned within the cut out portion, a card supported against the backing strip, a translucent cover member positioned over the card, and the adjacent edges of the translucent cover member and backing strip, being covered by cement.

5. A marker of the class described comprising a body portion having a head, said head having a cut out portion, a backing strip constructed of yieldable material positioned within the cut out portion, the edges of the backing strip extending outwardly, a card carrying indicia, positioned against the backing strip, the edges of the card contacting with the outwardly extended portions of the backing strip, a translucent member fitted against the card and held in position by a water proofing material positioned over the edges thereof.

In testimony that I claim the foregoing as my own, I have hereto affixed my signature.

HENRY JOHNSON.
